UNITED STATES PATENT OFFICE.

TOMASZ SZUTKOWSKI, OF SOUTH CHICAGO, ILLINOIS.

COMBINATION PADLOCK.

Application filed November 28, 1922. Serial No. 603,723.

To all whom it may concern:

Be it known that I, TOMASZ SZUTKOWSKI, a citizen of Poland, residing at South Chicago, in the county of Cook and State of Illinois, 5 have invented certain new and useful Improvements in Combination Padlocks, of which the following is a specification.

This invention relates to combination locks, being intended more particularly for 10 embodiment in a combination lock, the invention having for an object to provide a simple, efficient and inexpensive combination padlock.

For further comprehension of the invention, and of the objects and advantages thereof, reference will be had to the following description and accompanying drawings, and to the appended claim in which the various novel features of the invention 20 are more particularly set forth.

Fig. 1 of the drawings is a perspective view of a combination padlock constructed according to my invention.

Fig. 2 is a detail perspective view of the 25 shackle.

Fig. 3 is a perspective view of the lock with the shackle removed, this view showing the interior construction of the padlock.

Fig. 4 is a detail perspective view of one 30 of the rotary locking rings.

Fig. 5 is an axial sectional view of the padlock, with the shackle locked in place.

Fig. 6 is a fragmentary longitudinal sectional view showing one leg of the shackle.

In constructing my improved padlock I 35 provide a solid central body 10 of cylindrical form and having diminished studs 11 projecting from opposite ends thereof to hold in place a pair of disk-heads 12, 13 which are of somewhat larger diameter than 40 the body, these disk-heads having suitable central apertures through which the studs 11 pass, the ends of the latter being riveted down on the heads to fix the heads on the 45 ends of the body 10.

Extending from end to end of the body 10, on opposite sides thereof, are grooves 14 and 15 respectively which receive the 50 legs of the shackle 16 which is of substantially U-shape with parallel legs 16' and 16'', the former of which engages in the groove 14 and the latter in the groove 15. Formed in the head 12 are a pair of apertures 17 and 18 through which the respective legs 55 16' and 16'' of the shackle are inserted, while the head 13 has an aperture 19 therein to

receive the tip of leg 16' which latter is slightly longer than the leg 16''.

The shackle leg 16'' is formed with a series of backwardly facing ratchet toothed elements 22, and adapted to be engaged by a series of rings 23, as here shown four in number, which freely surround the body 10 between the heads 12 and 13 thereof, and which engage the teeth 22 of the shackle 60 to lock the latter. Each of these rings has a notch 24 cut in the inner wall thereof to permit of withdrawal of the shackle, by rotating said rings until the notches 24 are all in registry with the shackle teeth 22. 65 The bores of the rings 23 are flared outwardly and backwardly as shown at 25 to cause the rings to clear the teeth 22 while said rings are being rotated. The rings 23 may each have a series of dummy recesses 70 75 26 formed in their forward faces to confuse anyone trying to work the shackle out by adjusting one ring after the other.

The rings 23 and heads 12, 13 are provided with suitable numbered markings such 80 as 28 to enable the rings to be properly positioned, with their notches 24 registering with the shackle leg 16''.

In Fig. 6 I have shown in detail the construction of the toothed elements 22. As 85 there shown the leg 16'' is provided with a longitudinal groove or recess 30 in which is freely mounted a bar 31 formed with ratchet teeth 22. This bar 31 is normally pressed outward by a bow spring 32 located 90 behind it in the recess 30, displacement of the bar 31 being prevented by means of studs 34 on the ends thereof engaging in transverse slots 35 at the ends of the groove 30. This construction enables the shackle 95 16 to be snapped into place irrespective of the positions of the rings 23. It will be understood, of course, that the opening in the head 12 will be suitably formed to permit of outward passage of the bar 31. 100

Having thus described my invention what I claim as new and desire to protect by Letters Patent of the United States is as follows:

A padlock comprising a solid body of cylindrical shape having integral diminished studs extending from opposite ends thereof, and longitudinal grooves formed in opposite sides thereof, a pair of disk-heads fitting against opposite ends of said body and being of larger diameter than the latter and being held in engagement with the said body 105 110

by the said studs, a series of rings of equal outside diameter to the said heads freely surrounding said body and each having its inner wall formed with a notch extending 5 completely therethrough in an axial direction, said rings also having a number of recesses extending partially therethrough, a shackle adapted to engage in the said grooves in the body, said shackle having one 10 leg formed with a longitudinal recess, a bar located in said recess and movable trans-

versely of itself therein, ratchet-like shouldered elements on said bar adapted to engage behind the said rings to hold the shackle in place, and a spring in said recess holding said bar, in position with the said shouldered elements projecting beyond the confines of the shackle leg. 15

In testimony whereof I have affixed my signature.

TOMASZ SZUTKOWSKI.
